UNITED STATES PATENT OFFICE.

EMIL JOSSE, OF WILMERSDORF, GERMANY.

CONDENSER.

SPECIFICATION forming part of Letters Patent No. 703,793, dated July 1, 1902.

Application filed May 17, 1901. Serial No. 60,644. (No model.)

To all whom it may concern:

Be it known that I, EMIL JOSSE, a subject of the Emperor of Germany, residing at Wilmersdorf, Germany, have invented certain new and useful Improvements in Condensers, of which the following is a specification.

This invention relates to an improved condenser which is intended principally for condensing what is known as "cold vapor" arising from sulfurous acid, ammonia, and the like. In its general construction the new condenser does not differ from the ordinary surface condensers in ships' engines, the essential feature of the invention consisting only in the arrangement of oblique partitions, upon which the condensed fluid can flow down and be conveyed to the discharge outlet by means of holes formed in the lowermost places in these partitions. In this manner the fluid deposited in the upper part of the condensing-chamber is prevented from dropping onto the pipes arranged below and impairing their efficiency by reason of the passage and transfer of heat being impeded or prevented.

A form of the new condenser is illustrated by way of example upon the accompanying drawings.

As will be seen, Figure 1 is a longitudinal sectional elevation upon line A B of Fig. 2, which latter is a transverse section of the condenser.

The cylinder *a*, which forms the condensing-chamber, is traversed by a set of very small horizontal pipes *b*, which are carried through the ends *c c*, in front of which chambers *e e* are formed by the ends or covers *d d*, these chambers serving for the admission, distribution, and discharge of the fluid. By means of transverse or slanting partitions in the chambers *e e* the fluid entering below at the left is forced to take the serpentine course indicated by the arrows.

The gases which are to be vaporized enter at *f* into the condensing-cylinder on the upper side, where the fluid is carried away, and the condensed vapor issues at *g* on the lower side. In order that the gases may be conveyed not only from above and around the pipes, but also have a motion in a direction

lengthwise of the cylinder imparted to them for completing the return motion, partitions *h i* are provided, the upper one of which runs from the right-hand end tube-plate and extends to nearly the other end plate, while the lower one has a correspondingly reversed position. The entering gases are thus forced to pass over the partition *h* to the left, between *h* and *i* to the right, and beneath *i* again to the right. The partitions *h i* are not horizontal, but inclined or slanting, and this has the important advantage that condensed fluid which is deposited on the partitions flows down the same and is conveyed to the discharge-outlet *g* through holes *h' i'* at the lowest points of the partitions *h i*. In this way the lower pipes are protected against having their effectiveness impaired by the dropping onto them of fluid, which would otherwise occur in consequence of the hindrance to the passage of the heat. Any number of these slanting or oblique partitions may be used.

Having described my invention, what I claim, and desire to secure by Letters Patent, is—

1. A condenser comprising a drum or casing with interior heads forming chambers at the ends, pipes connecting said chambers, and inclined partitions arranged in the casing between said heads.

2. A condenser comprising a drum or casing with interior heads forming chambers at the ends, pipes connecting said chambers, and inclined partitions arranged in the casing between said heads, said partitions extending from opposite heads to within a distance from the other heads.

3. A condenser comprising a drum or casing with interior heads forming chambers at the ends, pipes connecting said chambers, and inclined partitions arranged in the casing between said heads, said partitions being provided with discharge-apertures at their lowest points.

EMIL JOSSE.
